UNITED STATES PATENT OFFICE.

AMASA V. STEALY, OF ELKHART, INDIANA.

HOT-WATER OR STEAM BOILER.

1,088,474.

Specification of Letters Patent.

Patented Feb. 24, 1914.

Application filed May 9, 1912. Serial No. 696,236.

To all whom it may concern:

Be it known that I, AMASA V. STEALY, a citizen of the United States, residing at Elkhart, in the county of Elkhart and State of Indiana, have invented a new and useful Hot-Water or Steam Boiler, of which the following is a specification.

My invention relates to boilers in which water is heated for the purpose of heating buildings and the objects of my improvement are, first, to have rapid circulation of water through the boiler; second, to make the heating area as large as possible; third, to arrange the fire pot so that the area of the grate can be varied; fourth, to avoid horizontal movement of the water through the boiler; fifth, to use the hot products of combustion for preheating the water; sixth, to provide automatic means whereby the products of combustion will be shunted to the chimney each time the fire door is opened; seventh, to provide automatic means whereby a flue connecting the ash pit and chimney is opened each time the ash pit door is opened; eighth, to make a cheap, durable and efficient boiler and other features to become apparent from the description to follow.

In boilers used to heat water it is very desirable to have the greatest efficiency with the least possible waste of fuel, to avoid dust and smoke in the room when feeding in fuel or removing ashes, to preheat or gradually heat the water, to have the water moving upward during the time it is being heated, to be able to change the size of the grate without changing the size of other parts, to have a large heating area and to have the water circulate through the boiler rapidly. A boiler in accordance with my invention contains all these desirable features, and comprises a rectangular trough like water jacket having its two sides flaring outward and upward so that a grate placed between these side walls can be of any desired width, the larger being placed higher in the trough-like jacket than the smaller. Suitable intake pipes are connected between the bottom of the water jacket and a header and suitable outlet pipes which are arranged in a novel manner are connected between the top of the water jacket and a header.

To describe my invention so that others versed in the art to which it pertains can make and use the same I have illustrated it on the accompanying two sheets of drawings

forming a part of this specification in which:—

Figure 1, is a vertical cross sectional view taken on line 1—1 of Fig. 2, and Fig. 2 is a vertical longitudinal section taken on line 2—2 of Fig. 1, partly broken away for the purpose of better illustration.

Similar reference characters refer to similar parts throughout both views.

A trough-like water jacket 3, made of sheet metal, serves as the receptacle for the fire box and ash pit, the flat bottom 4 of the water jacket being also the bottom of the ash pit and the two upright sides 5 of the water jacket serving as the side walls of the ash-pit and fire box. The inner and outer sheets of the water jacket 3 are secured together by suitable tie bolts 6. The upright side walls 5 are inclined outward so that the distance between their lower edges is considerably smaller than the distance between their upper edges, which enables varying the size of the grate 7 which spans the space between the walls 5 at such a height above the bottom 4 to suit the size or width of the grate; i. e., a small size grate would be placed down close to the bottom 4 and a large size grate would be secured in position a considerable distance above the bottom 4. The size of the grate, of course, determines, to some extent, the quantity of fuel consumed by the furnace. To aid the combustion the side walls of the fire box are lined with fire-brick 8.

As clearly shown in Fig. 2, the front end of the water jacket 3, is rigidly secured to the front plate 9 which extends over the entire front end of the boiler, its lower end resting in the wall 10, and its upper end secured to the upper header 11. The rear end of the water jacket 3 is rigidly secured to the rear plate 12, which extends over the entire rear end of the boiler, its lower end resting on the outer side walls 13 as seen at 14, Fig. 1, and its upper end secured to the upper header 11.

Communicating with the interior of the bottom 4 is a system of pipes or tubes 15 arranged staggered to admit the passage of hot gases therebetween, having their lower ends 105 communicatively connected with the lower header 16. The position of these tubes 15 is best seen in Fig. 2, which is, starting at the bottom, downward at right angles to said bottom, thence back and downward on an incline and finally down substantially vertically to the lower header 16.

Secured to the inside sheet of each side wall 5 near the top thereof are two rows of tubes which extend a short distance at right angles to their respective sheets, thence upward on an incline toward the center of the fire-box and finally upward substantially vertically to the lower side of the header 11 to which the said tubes are secured. These two rows of tubes are arranged staggered at each end where they are secured in the sheet metal plates but for the greater portion of their length they lie in the same plane and are arranged close together so as to present a corrugated surface to the hot gases above the fire-box, the back or upper side of said corrugated surface formed by the tubes 17 is covered by fire-brick 18 which has its lower ends resting on the top of the walls 5 of the water jacket 3. Secured to the bottom plate of the upper header 11 between the double rows of pipes 17 are the upper ends of a center row of tubes 19 which ends are alternately staggered so as to enable securing said tubes to the bottom plate of the upper header 11 and still have the tubes so close together that they will substantially touch throughout their greater length where they are formed to lie in the same vertical plane and serve as a central vertical partition extending longitudinally over the center of the grate 7. At a suitable distance above the grate the tubes 19, forming said central partition, are alternately bent toward either side and have their lower ends secured to the opposing plates of the upright side walls 5 just below the tubes 17. Thus it will be seen that the water within the boiler is free to circulate from the lower header 16 upward through tubes 15, upward through the jacket 3, thence upward through tubes 17 and 19 and finally into the upper header 11. From the upper header the water is conducted to the heating radiators not shown through the pipes 20 connected to the top of the upper header 11, and is returned from the radiators through pipes 21 to the lower header 16.

The hot gases from the fire-box, pass upward between the tubes 19 where they extend on an incline and on either side of said tubes 19 where they extend vertically coming into direct contact with the inclined tubes 17 on either side and thence pass upward and to either side between the staggered upper ends of the tubes 17 and 19, and over the tops of the fire-brick 18, thence on an incline downward between the fire-brick 18 and the outer walls 13, thence downward between the upright walls 5 of the water jacket 3 and the outer walls 13, thence horizontally underneath the bottom 4 of the water jacket 3 and between the pipes or tubes 15 and finally rearwardly between the tubes 15 into the chimney 22.

It will be noted that the gases emitted from the fire-box come in contact with the uppermost part of the water containing apparatus when hottest, viz., the tubes 17 and 19 and the upper header 11 just before the water passes through the pipes 20 to the radiators; and the same gases of combustion after partly cooled just before they pass into the chimney 22, contact with the lowermost part of the water containing apparatus viz., the tubes 15 and the lower header 16. By this manner of having the hot gases and the water traveling in opposite directions I attain the much desired effect of preheating the water, heating the water gradually and utilizing substantially all the heat carried by the gases of combustion.

By having the ash pit formed in the lower part of the water jacket 3 a considerable amount of heat is transferred from the ash pit to the water in the jacket which heat, in the ordinary construction of furnaces is wasted.

The outer walls 13 at the top terminate in curved portion 23 which extend to the sides of the upper header 11 and extend longitudinally from the front plate 9 to the rear plate 12. The outer side of the front and back plates 9 and 12 are covered with fire brick 24 or other material which is a non-conductor of heat, to prevent the radiation of heat.

I prefer placing a central longitudinal partition 25 below the bottom 4 of the water jacket 3 to equalize the quantity of hot gases of combustion, which pass down on either side of the water jacket 3. Suitable transverse partition 26 is placed directly below the rear plate 12 to confine the hot gases to the spaces between the tubes 15.

The fire box is provided with a door 27, the ash pit is provided with a door 28 and a cleanout door 29 is provided for the opening 30 leading to the pit below the water jacket 3, which is also used as a check on the fire.

A blow off pipe 31 provided with a stop cock 32 is secured to the bottom of the lower header 16.

It will be noted that the construction of the flues for the hot gases of combustion are so arranged that all dust and soot will lodge in the lowermost pit and on no surface of any water containing compartment, so that there is no waste of heat on account of soot or dust.

A flue 33 forms communication between the upper rear part of the fire box and the chimney 22 to provide a direct draft. The flue 33 is normally closed by a damper 34, which is weighted to normally rest in a closed position.

To prevent any smoke or dust passing out through the firing door 27 when it is opened

to feed fuel into the fire box I arrange means whereby the damper 34 in flue 33 is opened automatically each time the door 27 is opened: to the end a vertical rod 35 is secured to rotate with the pivot or pintle of the door 27. The upper end of the rod 35 is provided with a crank arm 36, which is connected by means of a rod 37 with one arm of the bell crank lever 38 pivoted at 39: the other arm of the bell crank lever 38 is connected by means of a rod 40 to the damper 34 in such manner that the damper will be opened when the door 27 is opened. Thus the draft will be shunted through the flue 33 to the chimney 22 whenever the door 27 is opened and the smoke and dust will be drawn out through the chimney.

As shown the lower end of rod 40 is slotted to provide lost motion between the door 27 and the damper 34 so that the damper 34 can be opened without the door 27 being opened.

Another flue 41 is connected between the rear end of the ash pit and the chimney 22 to draw out all dust and ash from the ash pit when the door 28 is open to remove the ash from the pit. I prefer to provide means whereby the damper 42 in pipe 41 is automatically opened every time the door 28 is opened, and to this end the damper 42 is weighted to normally rest in a closed position and is connected by rod 43 to one arm of the bell crank lever 44 pivoted at 45': the other arm of the bell crank lever 44 is connected by rod 45 to the crank arm 46 secured on the upper end of rod 47 which is secured to rotate with the pivot or pintle on which the door 28 swings. The parts are so connected and arranged that the damper 42 will be moved to an open position whenever the door 28 is opened and the damper 42 will be moved to a closed position whenever the door 28 is closed. Thus the draft will be shunted through flue 41 into the chimney 22, whenever the door 28 is opened, and carry all dust and ash into the chimney.

I desire to have it understood that the size form and arrangements of some of the parts can be radically varied without in the least departing from the scope of the invention as described above and hereinafter claimed.

Having thus fully described my invention what I claim as new and desire to secure by Letters Patent of the United States is:—

1. In a device of the class described, a trough like water jacket, a grate, ash pit and fire box arranged in said water jacket, a suitable header below said water jacket connected by a plurality of tubes to the water jacket and a suitable header above the said water jacket connected by a plurality of tubes to the sides of the water jacket.

2. In a device of the class described, a trough like jacket containing a grate, ash

pit and fire box, a suitable header above said water jacket connected by a plurality of tubes to the upper part of the sides of the water jacket, front and back plates closing the ends of the water jacket and extending upward to the header and flues for hot gases so arranged that the hot gases will contact with the water containing apparatus while passing in a downward course.

3. In a device of the class described, a trough like water jacket, containing a grate, ash pit and fire box, suitable outlet pipes connected to the upper part of the sides of said water jacket and suitable inlet pipes connected to the lower part of said water jacket.

4. In a device of the class described, a trough like water jacket, containing a grate, ash pit and fire box, a suitable header above said water jacket, a row of pipes connected to the top of either side of said trough like jacket extending upward in two converging inclined planes and having their upper ends connected to said header.

5. In a device of the class described, a trough like water jacket, containing a grate, ash pit, and a fire box, a suitable header above said water jacket, a row of pipes connected to the top of either side of said trough like jacket extending upward in two converging inclined planes having their upper ends connected to said header and suitable layers of fire brick on said inclined pipes extending up from the top edge of either side of the trough like jacket to a short distance below said header.

6. In a device of the class described, a trough like water jacket, containing a grate, an ash pit and fire box, a suitable header above said water jacket, a row of pipes connected to the top of either side of said trough like water jacket extending up therefrom in two converging inclined planes having their upper ends connected to said header, and a second row of pipes connected to the top of either side of said trough like water jacket said rows of pipes extending toward one another in two slightly inclined converging planes to the center of the jacket and thence vertically to said header to which they are connected.

7. In a device of the class described, a trough like water jacket containing a grate, ash pit and fire box, a suitable header below said water jacket, a plurality of pipes forming communication between said jacket and said header and suitable outlet pipes connected to the upper end of the sides of said jacket.

8. In a device of the class described, a trough like water jacket containing a grate, ash pit and fire box, a suitable header above said water jacket and a row of pipes connecting each side of said trough like water jacket with said header, the pipes in each of

said rows lying close together throughout the greater part of their length to present a corrugated surface to the hot gases and the extremities of said pipes being bent to have their ends arranged staggered where they are secured to the jacket and to the header.

9. In a device of the class described, a trough like water jacket containing a grate, 10 ash pit and fire box, a suitable header above said water jacket and two rows of pipes, one connected to either top side of the trough like jacket forming communication between 15 said water jacket and said header, the pipes of each of said rows extending from their respective top side of the trough like water jacket toward each other in slightly inclined converging planes, thence vertically in the same plane to the header to form a vertical 20 wall over the center of the fire box and spaced pipes over the whole fire box.

10. In a device of the class described, a suitable water jacket, a grate, ash pit and fire box in connection with said water jacket, 25 a suitable header below said water jacket connected by a plurality of tubes to said water jacket and a suitable header above 30 said water jacket connected by a plurality of tubes to the opposite sides of the water jacket.

11. In a device of the class described, a suitable water jacket, a grate, ash pit and fire box in connection with said water jacket, a suitable header above said water jacket connected by a plurality of tubes to the upper part of the sides of the water jacket, front and back plates in contact with said water jacket and extending upward to the header and flues for hot gases so arranged 40 that the hot gases will contact with the water containing apparatus while passing in a downward course.

12. In a device of the class described, a suitable water jacket having two sides, a 45 grate, ash pit and fire box in connection with said water jacket, a suitable header above said water jacket, a row of pipes connected to the top of either side of said water jacket extending upward in two converging inclined planes and having their upper ends connected to said header.

13. In a device of the class described, a suitable water jacket having two sides, a 50 grate, ash pit and fire box in connection with said water jacket, a suitable header above said water jacket, a row of pipes connected to the top of either side of said water jacket extending upward in two converging

inclined planes having their upper end connected to said header and suitable layers of 60 fire brick on said inclined pipes extending up from the top edge of either side of the said water jacket to a short distance below said header.

14. In a device of the class described, a 65 suitable water jacket having two sides, a grate, ash pit and fire box in connection with said water jacket, a suitable header above said water jacket, a row of pipes connected to the top of either side of said water jacket 70 extending up therefrom in two converging inclined planes having their upper ends connected to said header, and a second row of pipes connected to the top of either side of said water jacket, said rows of pipes extending toward one another in two slightly inclined converging planes to a point above 75 the center of the fire box and thence vertically to said header to which they are connected.

15. In a device of the class described, a suitable water jacket having two sides and containing a grate, ash pit and fire box, a suitable header above said water jacket and a row of pipes connecting each side of said water jacket with said header, the pipes in each of said rows lying close together throughout the greater part of their length to present a corrugated surface to the hot gases and the extremities of said pipes being 90 bent to have their ends arranged staggered where they are secured to the jacket and to the header.

16. In a device of the class described, a suitable water jacket having two sides and 95 containing a grate, ash pit and fire box, a suitable header above said water jacket and two rows of pipes forming communication between said water jacket and said header, one connected to either top side of the water 100 jacket, the pipes of each of said rows extending from their respective top side of the water jacket toward each other in slightly inclined converging planes, thence vertically in the same plane to the header 105 to form a vertical wall over the center of the fire box and spaced pipes over the whole fire box.

In testimony whereof I have signed my name to this specification in presence of two 110 subscribing witnesses this 30th day of December, 1912, at Chicago, Illinois.
